UNITED STATES PATENT OFFICE.

SAMUEL C. BOND, OF HOLLYOAK, DELAWARE, ASSIGNOR TO BOND BOTTLE SEALING COMPANY, OF WILMINGTON, DELAWARE, A CORPORATION OF DELAWARE.

METHOD FOR THE MANUFACTURE OF BOTTLE-CLOSURES.

1,087,095.

Specification of Letters Patent.

Patented Feb. 10, 1914.

Application filed May 5, 1911. Serial No. 625,214.

To all whom it may concern:

Be it known that I, SAMUEL C. BOND, a citizen of the United States, and a resident of Hollyoak, in the county of Newcastle and State of Delaware, have invented certain new and useful Improvements in Methods for the Manufacture of Bottle-Closures, of which the following is a specification.

My invention relates to improvements in method or process for the manufacture of that form of gas-tight bottle closures which consist of a metal cap carrying internally a gasket.

The metal cap which I use is of the usual well known form. It is generally annular in shape, has a substantially flat top and a depending flange or rim, substantially at right angles to the top, which is adapted to be crimped to the bottle top, and carries a gasket of some suitable material for forming a gas and liquid tight joint between it and the bottle top. In order that the gasket may not be displaced in shipment, in handling, or in the machine which caps the bottle, experience has shown that some means must be employed for so securely uniting these two parts that there will be no danger of their becoming accidentally separated, and my present invention relates to an improved method or process for accomplishing this end. Heretofore this has been accomplished by assembling the metallic cap and sealing gasket with a cementing medium interposed, then heating the whole with

or without the applications of pressure, the heat being employed to fuse the cementing material and the pressure, if pressure be used, to hold the parts in contact until the fused cementing material sets. This method is objectionable for the reason that the sealing gasket, which usually contains or is treated with wax, glycerin, etc., and generally carries a considerable quantity of water, is apt to be unduly heated and dried and the substances with which it is treated are evaporated or their nature so changed as to lose their intended effect. My method of overcoming these objectionable features consists in first heating the metal cap, which may or may not during the process of heating, carry the cementing medium, and after this inserting the gasket, it being understood that there is always finally to be a cementing medium between the gasket and the cap.

The gasket and cap having been assembled are preferably, but not necessarily, subjected to sufficient pressure to hold them in close contact until the cementing material has set. As the surface of the metal cap is frequently sufficiently greasy to prevent the cementing medium from adhering to it properly this initial heating of the metal cap also serves to drive off the thin film of grease or oil, if such be present, and leave a surface to which there will be no question of the cementing medium adhering. The cementing material may be applied directly to the cap or gasket, or it may be carried by a collet of paper or other suitable material which is placed between the metal cap and the gasket.

The accompanying drawings which form part of this specification and in which similar numerals of reference indicate similar parts throughout the several views show a machine for carrying out my process.

In these drawings Figure 1, is a plan of the machine and Fig. 2, a side elevation of Fig. 1.

1 is a circular rotating plate furnished with pockets 2 for carrying the metal part 3 of the bottle closure. The parts 3 are placed in the pockets 2 in any suitable manner, by hand for instance,

4 is a gas burner for heating the plate 1 and the metal parts 3 of the closure. Before, during, or after the heating of the parts 3 a cementing material is placed in them.

The plate 1 is preferably circular and is rotated in any convenient manner to bring the heated caps 3 to a shifter 5 which sweeps them from plate 1 to a second rotating plate 6 furnished with pockets 7 similar to the pockets 2 in plate 1. The plate 6 forms part of a rotating head which carries plungers 8, actuated by springs 9, which engage the gasket, which has been placed in the heated caps 3 in any convenient manner, by hand for instance, and holds them under pressure until the cementing material has set.

10 is a stationary cam for engaging collars 11 on plungers 8 to lift these plungers clear of the caps 3 after the cementing medium is set.

Although the drawings show a means for carrying out my process it will be understood that any other suitable machine may

be employed, this application relating rather to the process for the manufacture of the closures than to any means for carrying the process out.

5 Having thus described my invention I claim as new and desire to secure by Letters Patent:

1. In the manufacture of bottle closures composed in part of metal, the method or
- 10 process which consists in heating the metal part of the closure, inserting therein while cooling a collet of paper, or other suitable material, coated with a fusible cement thereby fusing the latter, depositing a sealing
- 15 gasket in the cap on top of the fused cement-

ing medium, and finally applying pressure to said parts until they are united.

2. In the manufacture of bottle closures composed in part of metal, the method or process which consists in heating the metal 20 part of the closure, inserting therein while cooling a collet of paper, or other suitable material, coated with a fusible cement thereby fusing the latter, and finally applying pressure to said parts until they are united. 25

SAMUEL C. BOND.
